Primary Examiner — Vy N Koenig(74) *Attorney, Agent, or Firm* — Hawaii Patent Services; Nathaniel K. Fedde; Kenton N. Fedde(57) **CLAIM**

The ornamental design for a hair dryer as shown and described.

DESCRIPTION

FIG. 1 is a front, right and top perspective view of a hair dryer showing my new design;

FIG. 2 is a rear, left and bottom perspective view thereof; FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of a portion labeled as 9 on FIG. 1; and,

FIG. 10 is an enlarged view of a portion labeled as 10 on FIG. 1.

The dash-dash broken lines illustrate portions of the article that form no part of the claim. The long dash-short dash broken lines depict enlargement boundaries that form no part of the claim.

1 Claim, 10 Drawing Sheets(56)
